COMB

John Giacomo Pucci, Westerly, R. I.

Application March 29, 1940, Serial No. 326,712

4 Claims. (Cl. 132—18)

My invention relates to improvements in combs.

An object of my invention is to provide a novel type of parting tooth differing from the standard comb teeth and having a plow-like action adapted to form a parting line, no matter where located on the comb.

While I am aware that others have provided combs having various types of enlarged parting teeth, so far as I am aware no one has provided a comb with a parting tooth having a plow-like action of the type employed by me, said parting tooth being generally shaped in the form of a plow and being triangular in horizontal section and preferably with the walls of said triangle also converging substantially to a parting tip substantially at the front of the lower end thereof, so that the tip may project downwardly between the individual hairs to provide a true parting line, permitting the parting tooth to provide a point and apex even if tilted forwardly or backwardly, as is often done in combing the hair.

A further object of my invention is to provide a novel type of parting tooth which may be located at any desired position on the comb, either at the end thereof to supplement the end-wise action of a comb, often employed to provide a parting line, or centrally thereof to provide a parting line as the comb is combed forwards or backwards.

A further feature of one embodiment of my invention, however, is to locate my improved parting tooth with groups of the regular row of aligned teeth on each side thereof, preferably with the parting tooth located centrally thereof to have similar groups of an equal number of teeth on each side thereof projecting downwardly not at right angles to the plane of the comb, but with walls substantially parallel to the respective side walls of the parting tooth and similarly inclined relative to a perpendicular to the comb as the forwardly tapering walls of said parting tooth to provide groups of oppositely inclined parallel grooves between them extending laterally on each side of each parting tooth.

An object of this type of construction is to provide a supplemental inclined harrowing action in addition to the plow-like action of the parting tooth to guide the hairs obliquely laterally from said parting tooth so that they may be more easily reached by the comb or brush in laying them in directions generally perpendicular to

the parting line. Should an oblique part be desired, however, it is possible to regulate the walls of the parting tooth and the inclined teeth to provide a parted head of hair by a single motion of the comb with the hairs projecting obliquely laterally at the desired angle from the parting line.

A further object of this embodiment of my invention where the groups of inclined teeth are employed on each side of the parting tooth, is to provide a comb having a certain amount of curling action on the hairs as being laid.

A further object of my invention is to provide a comb with the advantages described above which may be readily molded or fabricated in as simple a fashion as the standard molding or manufacturing of a standard type of comb.

These and such other objects of my invention as may hereinafter appear will be best understood from a description of the accompanying drawing, which illustrates embodiments thereof.

In the drawing, Fig. 1 is a front elevation illustrating a comb constructed in accordance with one embodiment of my invention.

Fig. 2 is a rear elevation of the comb shown in Fig. 1.

Fig. 3 is a reverse plan view of the comb shown in Figs. 1 and 2.

Fig. 4 is a horizontal sectional view taken along the line 4—4 of Fig. 1.

Fig. 5 is a horizontal sectional view taken through a different embodiment of my invention wherein the groups of standard teeth on each side of the parting tooth are inclined at different angles adjacent the parting tooth and are arranged in the usual shape of comb teeth perpendicular to the comb at the outer ends of each group thereof.

Fig. 6 is a diagrammatic plan view of a portion of a scalp showing a portion of a comb constructed as shown in Figs. 4-5 in the act of plowing a parting line as the comb is brought forwardly or rearwardly over the scalp inclined relative thereto.

Fig. 7 is a slide elevation of an end portion of a different embodiment of my invention having my improved parting tooth located as the end tooth of the comb with its apex facing inwardly.

Fig. 8 is a reverse plan view of the portion of the embodiment of comb shown in Fig. 7.

In the drawing, wherein like characters of reference indicate like parts throughout, 10, 10', 55,

and 10" generally indicate embodiments of combs constructed in accordance with my invention.

Each embodiment of comb has teeth projecting downwardly from the upper portion 12, 12' and 12" thereof, one of said teeth comprising a parting tooth 14, 14' or 14" and my invention specifically relates to the construction of such a parting tooth which I preferably employ. The parting tooth is of solid triangle formation, has a rear wall 16, 16' and 16" comprising a triangle base and preferably equi-lateral side walls 18, 18' or 18" tapering forwardly substantially to a front apex line 20, 20' or 20", said side walls 18, 18' and 18" tapering forwardly at least 20° from the perpendicular to the comb, in the embodiment shown substantially at 30°. Said solid triangle extends downwardly substantially to the lower end of said tooth. In the preferred embodiments shown, the lower ends of the walls of said triangle converge as at 22, 22' or 22" for the edges of the triangle base 14, 14' or 14" thereof and as at 23, 23' or 23" for the lower end of said triangle base itself and as at 24, 24' or 24" for the lower ends of each of the side walls 18, 18' or 18", substantially to a parting tip or point 26, 26' or 26" substantially at the lower end thereof, as it is desirable to have the parting tooth terminate at a point to separate the individual hairs, whether the comb be held 90° to the scalp as it passes thereover, or inclined relative thereto, as shown in Fig. 6. If the comb be inclined backwards while parting the hair 30 on the scalp 32 as shown in Fig. 6, it is obvious that the point 26 will separate the roots of the individual hairs adjacent the scalp and that the inclined side walls thereof will separate the portions of the hairs above the roots obliquely laterally as shown at 34 therein to provide the parting line 36 in rear of the apex 20 of said tooth. If the comb is tilted backwards, as suggested in Fig. 6, it is obvious that the pointed triangular apex 23 will lie flat on the scalp, as shown in Fig. 6 to assist in the plow-like action. In addition to the parting tooth 14, 14' or 14", 45 supplemental teeth 38 or 38' or 38" of the standard type are preferably provided to make up the comb which may be aligned as usual in a row 40, 40' or 40". In the preferred embodiments of my invention shown in Figs. 1-5, however, 50 groups 38^a and 38^b of teeth are located on each side of said parting tooth, the teeth of each group having side walls 42^a and 42^b substantially parallel to the respective side walls 18 of said parting tooth and similarly inclined, to provide groups 55 of oppositely inclined parallel grooves 44^a and 44^b between them for curling the hairs and urging them in opposite directions obliquely outwardly from said parting tooth 14, this action being suggested by the hairs 30 and 34 shown in Fig. 4, 60 the hairs 34 extending obliquely outwardly after passing through the respective grooves or passageways 44^a and 44^b between the respective teeth of each group 38^a and 38^b and the respective side walls 18 of said parting tooth. It is apparent 65 that these groups tend to lay all hairs on each side of the parting line 36 at an angle corresponding in obliquity to the amount that the respective side walls of said respective teeth are inclined. It is then obvious that if it be desired 70 to brush the hair to substantially 90° from the parting line 36 that the hairs may be readily picked up by a brush and so moved to be readily laid in this direction. As suggested in Fig. 6 a single movement of the comb forward over the 75 hair is sufficient to provide the parting line 36

with the hairs extending obliquely from said parting line as at 34 throughout the desired portion of the scalp reached by the comb so that they may be readily picked up and moved at a greater angle to the parting line by a single action of a 5 brush if desired. The movement of the hairs through the respective passages 44^a and 44^b as illustrated centrally of Fig. 4 and as suggested as at 35 at a side thereof functions to impart a curling or crinkling effect to the hairs passed 10 through the respective passageways. As stated previously, the respective groups of inclined teeth 38^a and 38^b function in supplement to the plow-like action of the parting tooth 14 as inclined harrows to urge the hairs obliquely outwardly 15 from the parting line and additionally function to aid in providing a curling or crinkling effect to the hair.

In the embodiment of my invention shown in Fig. 5 the grooves 44^a and 44^b are not similarly 20 inclined all the way out, but each successive groove 44^a and 44^b may be inclined outwardly 25 lesser amounts from the center tooth 14' until the teeth in the respective groups are substantially at right angles to the comb as the exterior teeth 46 shown therein. Thus a comb may be provided with groups of inclined teeth near the center thereof to function in accordance with my invention and groups of standard teeth exterior thereof to function in the ordinary fashion. 30

I have shown in Figs. 7 and 8 an embodiment of my invention employing my improved parting tooth 14" in which the triangle base 16" is located at the end surface of the comb and in which the side walls 18" thereof taper inwardly 35 towards the usual row 40" of standard aligned comb teeth 38" arranged as usual perpendicular to the comb, to a front apex line 20" facing said row of teeth. It has been standard practice to use the edge of the comb to make a parting line 40 and a comb constructed in accordance with the embodiment of my invention shown in Figs. 7 and 8 functions in similar manner to provide a better parting line.

It is apparent that I have provided a novel 45 type of comb having a novel type of parting tooth which may be employed alone or in association with groups of obliquely inclined teeth in the manner shown with the advantages described 50 above.

It is understood that my invention is not limited to the specific embodiments shown and that various deviations may be made therefrom without departing from the spirit and scope of the appended claims. 55

What I claim is:

1. A comb having teeth projecting downwardly from the upper portion thereof comprising a central parting tooth triangular in section substantially throughout the height thereof having a rear wall comprising a triangle base and equilateral side walls converging forwardly substantially to a front apex line at least 20° from the perpendicular to the comb with the rear and side walls of said triangle converging downwardly near the lower end thereof to a parting tip at the front of the lower end thereof and groups of teeth on each side of said parting tooth, each group having side walls substantially parallel to the respective side walls of said parting tooth and similarly inclined, providing groups of oppositely inclined parallel grooves between them for curling the hairs and urging them in opposite directions obliquely outwardly from said parting tooth. 60
2. A comb having teeth projecting downwardly 65

70

75

- from the upper portion thereof comprising a parting tooth triangular in section substantially throughout the height thereof having a rear wall comprising a triangle base and equilateral side walls converging downwardly near the lower end thereof to a parting tip at the front of the lower end thereof.
5. walls converging forwardly substantially to a front apex line at at least 20° from the perpendicular to the comb with the rear and side walls of said triangle converging downwardly near the lower end thereof to a parting tip at the front of the lower end thereof and supplemental teeth associated with said parting tooth to provide a comb.
10. lower end thereof and supplemental teeth associated with said parting tooth to provide a comb.
3. A comb having a parting tooth triangular in section substantially throughout the height thereof projecting downwardly from the upper portion thereof having a rear wall comprising a triangle base and equilateral side walls converging forwardly substantially to a front apex line at at least 20° from the perpendicular to said tooth
15. with the rear and side walls of said triangle converging downwardly near the lower end thereof to a parting tip at the front of the lower end thereof.
4. A comb having teeth projecting downwardly 5 from the upper portion thereof comprising a row of aligned teeth and an end tooth triangular in section substantially throughout the height thereof comprising a parting tooth have a rear wall comprising a triangle base at the end surface of 10 said comb and equilateral side walls converging inwardly towards said row of aligned teeth substantially to a front apex line and with the side and end walls of said triangle converging downwardly near the lower end thereof to a parting 15 tip at the front of the lower end thereof.

JOHN GIACOMO PUCCI.
